2 SHEETS—SHEET 2.

UNITED STATES PATENT OFFICE.

MELVIN B. BENSON, OF SUPERIOR, WISCONSIN.

TELEMOTOR.

1,345,060.

Specification of Letters Patent. Patented June 29, 1920.

Application filed December 3, 1918. Serial No. 265,162.

To all whom it may concern:

Be it known that I, MELVIN B. BENSON, a citizen of the United States, residing at Superior, in the county of Douglas and State 5 of Wisconsin, have invented certain new and useful Improvements in Telemotors, of which I do hereby declare the following to be a specification.

My invention relates to telemotors and has 10 for one of its objects the provision of improvements in steering gear for vessels. It has for a further object the provision of improved means for operating the valve of an engine distant from the station of the operator. Heretofore the operative action of 15 devices of this type has tended to continue, by reason of momentum, longer than desired, and to carry certain transitory or reciprocable parts of the device past the stations 20 at which they were intended to stop. One feature of my invention is the provision of a simple and efficient automatic brake to compensate such tendency. With these and other objects in view, it consists of the constructions, combinations and arrangements 25 of parts hereinafter described and claimed.

In the drawings, Figure 1 is a diagrammatic plan view of one form of structure embodying my said invention. Fig. 2 is a 30 central vertical section, partly in side elevation, of a hereinafter described controller case and contents, forming part of my said invention. Fig. 3 is a fragmentary top plan view, partly in central horizontal section 35 and partly broken away, of a hereinafter described reciprocable collector bar contact and series of opposed stationary contacts.

In the drawings, 1 is a source of electricity as a generator of any suitable type, one 40 of the poles, as the plus pole, of which generator is electrically connected in any suitable manner, as by a wire 1^a, post 1^b, rail 1^c, contact point 1^d, and wire 1^e, with a contact point 1^f, which latter point is adapted to be 45 moved by any suitable means as by a lever 2, spindle 2^a, and contact supporting arm 2^b, into contact with one or another of a plurality of stationary contact points 3, 4, 5. Said pole of said generator is also connected in 50 any suitable manner as by a wire 1^g with one pole of the shunt field 6 of a motor 7 of any suitable type, and is also connected through a normally open contact 8, and wire 9 with one of the armature poles as 7^a of said motor, and through said armature and wire 11 55 and a normally open contact 15 and wire 13

with one of the poles of a series field 14 for said motor. Said plus pole is also connected through said wire 1^e, a normally open contact 10 and wire 11 with the opposite pole 7^b of said armature, and through said armature and wire 9 and a normally open contact 12 and said wire 13, with said pole of said series field. The opposite pole of said series field is connected through wires 16 and 17 with 65 the opposite or minus pole, of said generator, and the opposite pole of said shunt field is connected through wires 18 and 17 with said opposite or minus pole of said generator. 70

Said plus pole of said generator is also connected through normally closed contacts 19 and 20 with one pole of an electromagnet 21, the opposite pole of which magnet is connected to said minus pole of said generator. 75 Said poles 7^a and 7^b of said motor are electrically connected to each other through a resistance 22 and a normally closed contact 23, which contact 23 is adapted to be closed by the operation of said magnet 21 upon an 80 armature 21^a of any suitable structure, by which one of the points of said contact 23 is carried or moved. Said contact points 3, 4 and 5 (it being understood that there may be any greater number of them, and an equal 85 number of the hereinafter described corresponding normally closed contact points) are connected by wires, as, respectively, 3^a, 4^a and 5^a with corresponding stationary contact points 3^b, 4^b and 5^b mounted in a support 90 24 of any suitable material or structure, as in a stationary block 24 of insulating material by which they are directly insulated from each other. Adapted to contact at various times with any one or another of said contacts 3^b, 4^b and 5^b, and at all times with all but one of them is a movable contact of any suitable structure, preferably of the reciprocable collector bar type, divided transversely into two sections as 25 and 25^a, by 95 an insulating block 27, which collector bar is mounted on a carriage 26 from which it is insulated by a strip 26^a of insulating material. Said block 27 is adapted to insulate any one or another of said contacts 3^b, 4^b and 5^b at various times from either of said sections 25 and 25^a. Said section 25 is electrically connected in any suitable manner, as by a stationary contact 28 adapted to bear thereon at all times, and by a wire 29, with one pole of a magnet 30 the opposite pole 100 of which is connected to the minus pole of 105

said generator. Said magnet 30 is adapted to simultaneously close the normally open contacts 8 and 15 by the operation of its armature 30^a by which one of the points 5 of each of said contacts is carried or moved; and at the same time said magnet is adapted to open the normally closed contact 19 by the operation of an armature by which one of the points of the latter contact is carried.

10 Said contact 25^a is connected in any suitable manner, as by a stationary contact 31, adapted to bear thereon at all times, and a wire 31^a with one pole of a magnet 32, the opposite pole of which is connected to the minus 15 pole of said generator. Said magnet 32 is adapted to simultaneously close the normally open contacts 10 and 12 by the operation of an armature 32^a of any suitable structure by which one of the points of each of said contacts 20 is carried or moved; and at the same time said magnet 32 is adapted to open the contact 20 by the operation of an armature by which one of the points of the latter contact is carried or moved.

25 Said carriage 26 is adapted to be operated by said motor through any suitable transmission mechanism, preferably comprising a slidable block 33 adapted to be moved along guides, 34, 35 by a worm 36 journaled 30 in stationary bearings of any suitable construction as 37, 38; said worm engaging said block intermediate of its ends. Mounted on the shaft of said worm at one end is a gear 39 adapted to engage one of a train of gears 35 as 40, 41, the other of which train is adapted to be driven by a pinion 42 on the shaft of said motor. Pivotally secured at one end to said block is a link 43, adapted to be connected at its opposite end to the valve 40 stem (not shown) of a steam steering or other engine (not shown) for operating said valve.

Under the conditions shown in Fig. 1, the device is at rest, on center. In operation, 45 if the contact arm be moved so that the contact point 1^f covers the point 5, the current will flow from said generator to rail 1^e; thence to the point 1^d, to point 1^f, to point 5, by wire 5^a to point 5^b; thence 50 through contacts 25^a, 31 and magnet 32 back to the generator. The magnet 32 operates the armature 32^a, causing it to close the normally open contacts 10 and 12, and at the same time opens the normally closed contact 20. The current will then flow through the wire 1^e, normally open contact 10, wire 11, pole 7^b and armature of the motor 7, thence through the wire 9, normally open contact 12, wire 13, series field 14, and wires 55 16 and 17 back to said generator. The motor thereupon being energized and operating through the pinion 42, train of gears, worm and slidable block, moves said carriage so that the insulation block 27 is carried under said contact point 5^b, thereby

cutting off the current from the magnet 32, which thereupon drops its armature 32^a which opens the contacts 10 and 12, thus cutting off the current from said motor. At the same time said magnet drops the armature (if it be a separate one) which carries or moves one of the points of the contact 20, thus permitting said contact 20 to close. Thereupon, current from the generator will flow through wire 1^e, contacts 19 and 20, and the magnet 21, back to the generator, and at the same time through said wire 1^e, shunt field 6, wires 18 and 17 back to the generator. The magnet 21 attracts its armature 21^a, causing it to close the contact 23, whereupon the poles of said armature become short circuited through wires 9 and 11, resistance element 22 and contact 23. The motor, under previously acquired momentum, thereupon operates as a generator and automatic brake, the excess energy of which is absorbed or neutralized by said resistance element, and the operation of said motor is thus promptly stopped. In like manner the movement of the carriage may be continued in the same direction, by the addition of points and wires similar to said points and wires 5, 5^a and 5^b successively at further distances from said point 4, and by electrically connecting said point 1^f with any one of them; the carriage continuing its movement in the same direction until the insulation block 27 cuts the circuit.

If at any time the point 1^f is brought into 100 electrical communication with a point similar to point 4 at the opposite side of the temporary position of the insulation block 27, the rotation of said motor and of the movement of said carriage will be reversed 105 as follows: The current from said generator 1 will then travel through section 25 of said collector bar; thence through the wire 29 and magnet 30 back to the generator. Said magnet 30 will operate its armature 110 30^a causing it to close contacts 8 and 15, and at the same time open the contact 19 and thus cut the circuit through said resistance. The current from the generator 1 will now flow through the wire 1^e, contact 8, wire 9 115 pole 7^a and motor 7; thence by wire 11 contact 15 wire 13 series field 14 wires 16 and 17 back to said generator. The motor will therefore be reversed, and through said pinion, gears, worm and sliding block will move said 120 carriage in said opposite direction until said insulation block 27 cuts the current from said magnet 30. Thereupon said magnet 30 will drop its armature, or armatures, thus opening the contacts 8 and 15 and closing 125 the contact 19. The current from the generator to the motor will thus be cut, and the circuit from the motor-generator through the resistance 22 will be established. At the same time the circuit through said series 130

field will be cut and established through said shunt field. It will be observed that the shifting of the block 27 back and forth operates to transfer a variable number of 5 the points 3^a, 4^b and 5^b temporarily from one circuit to another, according to the direction and distance that said block 27 is shifted.

Without said resistance circuit, the tendency would be for the momentum of the 10 motor to carry the insulation block 27 past the intended stopping point, thus permitting the circuit to close through the reversing section of the collector bar; and in like manner to shift said block back and forth for 15 gradually shortening distances until it came to rest at the proper position. The brake, therefore, is an important feature of the invention. Another feature is the construction 20 whereby said carriage and mechanical transmission and motor are compactly assembled, permitting the use of the device in torpedo boats and other small craft, as well as conserving valuable space in larger vessels in which the device may be used. Having now described my invention,

What I claim is—

1. The combination of an electric circuit comprising a source of electricity, a normally open contact, a motor armature, a second normally open contact, and a series field for said motor; a second electric circuit comprising said source a plurality of normally open contacts in parallel, a plurality of normally closed contacts in parallel, each of said closed contacts being in series with a corresponding one of said normally open contacts of said second circuit, and an electromagnet, said magnet being adapted to close the 35 normally open contacts of said first circuit; manually operable means for closing any one of the normally open contacts of said second circuit; means adapted to be mechanically operated by said motor to open any 40 one of said normally closed contacts of said second circuit after the corresponding normally open contact of said second circuit has been closed; a third electric circuit, comprising said source, a normally closed contact 45 adapted to be opened by said magnet, and a second electromagnet; a fourth electric circuit comprising the armature of said motor, a normally closed contact governed by said second magnet, and a current resistance element; and a fifth electric circuit comprising said source and a shunt field for said motor.

2. The combination of a circuit including a source of electricity, a normally open contact, the armature of an electric motor, a 50 second normally open contact, and the field of said motor; a second electric circuit including said source, a plurality of normally open contacts in parallel, a plurality of normally closed contacts in parallel, each of said normally closed contacts being in series

with a corresponding one of the normally open contacts of said second circuit; means for closing any one of the normally open contacts of said second circuit; means for automatically opening the corresponding 70 one of said normally closed contacts after the closing of any one of the normally open contacts of said second circuit; a third electric circuit including the armature of said motor, a normally closed contact and a resistance element; a fourth electric circuit including said source a normally closed contact and a coil for magnetizing a translation device; means governed by said second circuit for closing the first and second normally open contacts of said first circuit and for opening the normally closed contact of said fourth circuit; said translation device being adapted to close the normally closed contact of said third circuit when said first 80 circuit is open; the contact opening means of said second circuit being governed by said first circuit; and a fifth circuit comprising said source and a shunt field for said motor.

3. The combination of an electric circuit including a source of electricity, a normally open contact, the armature of an electric motor, a second normally open contact, and a series field for said motor; a second electric circuit including said source, a normally open contact, said armature, a second normally open contact, and said series field, said second circuit leading through said armature in a direction opposite to the direction of said first circuit therethrough; a 95 third electric circuit and a fourth electric circuit each including said source, a plurality of normally open contacts in parallel, and a plurality of normally closed contacts in parallel, each of said normally closed contacts being in series with a corresponding one of said normally open contacts; means for closing any one of the open contacts of said third or fourth circuit, said closing means being adapted in operation to relatively transfer a variable number of the open contacts of said third circuit temporarily to the fourth circuit, or vice versa; means for opening any one of the normally closed contacts of said third or fourth circuit, said opening means being adapted in operation to relatively transfer a variable number of said normally closed contacts from said third circuit temporarily to said fourth circuit, or vice versa; a fifth electric 100 circuit comprising said source, a normally closed contact, and a second normally closed contact; a sixth electric circuit comprising said armature, a normally closed contact and a resistance element; a seventh electric circuit comprising said source and a shunt field for said motor; means governed by said third circuit for closing the normally open contacts of said first circuit and for opening one of the normally closed contacts of said 105 110 115 120 125 130

fifth circuit; means governed by said fourth circuit for closing the normally open contacts of said second circuit and for opening the other normally closed contact of said 5 fifth circuit; means governed by said fifth circuit for closing the normally closed contact of said sixth circuit; and mechanical transmission means adapted to be driven by said motor for operating one of the contact 10 transfer means of said third and fourth cir-

cuits, the other contact transfer means of said third and fourth circuits being adapted to be manually operated.

In testimony whereof, I hereunto affix my signature, in presence of two witnesses.

MELVIN B. BENSON.
